UNITED STATES PATENT OFFICE.

MARTIN J. WEIL, OF NEW YORK, N. Y.

DESIGN FOR A CARDIGAN JACKET.

Specification forming part of Design No. 11,445, dated September 30, 1879; application filed July 25, 1879.
[Term of patent 7 years.]

To all whom it may concern:

Be it known that I, MARTIN J. WEIL, of the city, county, and State of New York, have originated and designed a Pattern for Cardigan Jacket, of which the following is a full, clear, and exact description, reference being had to the accompanying photographic illustration, making part of this specification.

The accompanying photographic view illustrates my design.

This design relates to Cardigan jackets or vests; and it consists, essentially, in the design of three longitudinal central bars, from which diverge other bars intersecting a lower transverse bar, as shown in the accompanying illustration.

The letter A indicates a Cardigan jacket or vest, and C D E three longitudinal central bars extending to and intersecting the upper one of two transverse bars, b b', which latter are joined by filling-threads c. From the longitudinal bars C D E divergent bars d e f intersect the transverse bar b.

The upper part or collar portion of the jacket or vest is substantially of the usual pattern or form.

By the characteristic features of my design—viz., the longitudinal central bars and the divergent bars intersecting the transverse bar—I provide a jacket of handsome and distinguishing appearance.

Having thus described my design, what I claim is—

The design for the back of a Cardigan jacket, consisting, essentially, of the central longitudinal bars C D E and divergent bars d e f, intersecting the transverse bar b, substantially as described, and shown in the accompanying illustration.

In testimony that I claim the foregoing I have hereunto set my hand and seal this 22d day of July, 1879.

MARTIN J. WEIL. [L. S.]
